UNITED STATES PATENT OFFICE.

PAUL THEURICH, OF DRESDEN, GERMANY, ASSIGNOR TO THE FIRM WEZEL & NAUMANN, AKTIENGESELLSCHAFT, OF LEIPZIG, GERMANY.

ADVERTISING PANEL OR DECORATIVE WALL COVERING.

Application filed June 12, 1925, Serial No. 36,680, and in Germany December 9, 1924.

This invention relates to advertising panels and decorative wall coverings and consists in this that the advertising matter or design is printed on an originally flat paper strip and is then pasted or otherwise caused to adhere after the manner of corrugated paper in waves to a flat background. The product thus obtained is of surprisingly attractive appearance produced by the 5 operation of the corrugated surface and the play of light and shade obtained thereby with the design (in which term is intended to be included the printed matter and pictures).
10 The impression produced by the usual corrugated paper in single colour or uniform colour is not to be compared with the impression produced by the product in accordance with the invention, which is that of a heavy plush or certain kinds of tapestry.
15 At a very low cost therefore panels or strips can be produced which are suitable as a background for window decorations, for covering show cases and like purposes.
20 The impression made by the printed matter, pictures or other designs makes a very notable impression due to their corrugated forms when viewed from a sharp angle, since from the same angle flat parts of the
25 corrugations are always presented which lie at right angles or approximately at right angles to the direction from which they are viewed, and thus an impression of a design is given which is different from that given
30 by a design on a flat surface.
35 Fig. 1 of the accompanying drawing shows the improved product in elevation.
Fig. 2 is a horizontal section, and
Fig. 3 shows the design given in Fig. 1
40 but on a flat paper strip.

Referring to the drawing, *a* denotes the flat background and *b* the covering strip shown corrugated in Figs. 1 and 2 and flat in Fig. 3. A comparison of Figs. 1 and 3 makes it clear how the design printed on the 45 flat covering strip intentionally distorted is transformed by corrugation into a design of the desired appearance in the completed product.

Having now particularly described and ascertained the nature of my said invention and in what manner the same is to be performed, I declare that what I claim is:—

1. A method of producing a decorative wall covering for advertising purposes, consisting in applying the design constituting the decorative or advertising matter in a distorted manner on a sheet having a flat surface, then corrugating said sheet and providing said corrugated sheet with a flexible 55 flat background permanently secured thereto.

2. An advertising or decorative panel comprising a corrugated paper sheet with a design applied thereto in distorted manner so that the design is rectified by the corrugations and a flat paper sheet applied to the back of said first sheet holding the individual 60 corrugations in position.

3. An advertising or decorative panel comprising a paper sheet having vertical 70 corrugations and a design applied thereto in distorted manner so that the same is rectified by the said corrugations and a flat paper sheet fixed to the back of said first sheet and holding said corrugations in position. 75

In testimony whereof I affix my signature.

PAUL THEURICH.
